US00D754673S

(12) **United States Design Patent**
Kim et al.

(10) **Patent No.:** US D754,673 S
(45) **Date of Patent:** ** Apr. 26, 2016

(54) **DISPLAY SCREEN OR PORTION THEREOF
WITH ICON**

(71) Applicant: **Samsung Electronics Co., Ltd.**,
Suwon-si, Gyeonggi-do (KR)

(72) Inventors: **Min-Sun Kim**, Seongnam-si (KR);
Eun-Young Kim, Seoul (KR)

(73) Assignee: **SAMSUNG ELECTRONICS CO.,
LTD. (KR)**

(**) Term: **14 Years**

(21) Appl. No.: **29/482,635**

(22) Filed: **Feb. 20, 2014**

(30) **Foreign Application Priority Data**

Aug. 22, 2013 (KR) 30-2013-0043079

(51) **LOC (10) Cl.** **14-03**

(52) **U.S. Cl.**
USPC **D14/485**

(57) **CLAIM**

The ornamental design for a display screen or portion thereof with icon, as shown and described.

DESCRIPTION

The FIGURE is a front view of a display panel or portion thereof with an icon, showing our new design.

In the drawings, the broken lines show a display screen or portion thereof with an icon and form no part of the claimed design.

1 Claim, 1 Drawing Sheet
